UNITED STATES PATENT OFFICE.

EDWARD A. MARTIN, OF NEWARK, NEW JERSEY.

DESIGN FOR AN EMBLEM.

No. 39,865.

Specification for Design.

Patented March 9, 1909.

Application filed December 1, 1908. Serial No. 465,585. Term of patent 7 years.

To all whom it may concern:

Be it known that I, EDWARD A. MARTIN, a citizen of the United States, and a resident of Newark, county of Essex, and State of New Jersey, have invented a new, original, and ornamental Design for Emblems, of which the following is a specification, reference being had to the accompanying drawing, forming part thereof.

The figure is a plan view of an emblem, showing my new design.

I claim:

The ornamental design for an emblem, as shown.

EDWARD A. MARTIN.
